S. L. RICHMOND

MEANS FOR DRY STORAGE

Filed April 22, 1927

Patented Nov. 15, 1927.

1,649,733

UNITED STATES PATENT OFFICE.

SAMUEL L. RICHMOND, OF BALBOA, CANAL ZONE, PANAMA.

MEANS FOR DRY STORAGE.

Application filed April 23, 1927, Serial No. 185,781, and in Panama April 1, 1927.

My invention relates to storage closets and particularly to closets for storing dry materials such as leather goods, clothing, chemicals, medicines, photographic supplies and steel instruments at atmospheric temperatures in hot, humid climates, and the object of my invention is to provide an apparatus for condensing and removing the moisture from such closets containing such articles.

10 Another object of my invention is to provide an apparatus wherein freezing brine such as is employed for freezing ice cream is used for condensing the moisture and thereby reducing humidity in storage containers or closets.

I accomplish the above and other objects of the invention by means of the construction shown in the accompanying drawing in which

20 Fig. 1 is a perspective of my invention showing the brine container removed from the closet, the supporting means on the interior of the closet being shown in dotted lines; and

25 Fig. 2 is a vertical section through a portion of the closet showing the brine container therein.

On the drawing, in which like reference characters indicate like parts on all the figures thereof

1 indicates a storage container or closet made of wood, metal, or other suitable material, which is approximately air tight; 2 indicates a partition therein dividing the closet into two compartments, a storage compartment 3 and a dehumidifying compartment 4. The partition is spaced from the top and bottom of the closet in order to provide for a circulation of air through the contents of the storage compartment and around the condensation unit.

All of this construction is shown and described in my copending application for a storage closet filed of even date herewith, the present application being a modification of the apparatus disclosed therein.

An opening 5 having a cooperating closure 6 is formed in the wall of the closet through which may be inserted the receptacle containing the freezing brine. Attached to the partition 2 are trackways 7, said trackways having outturned end portions 8 which are secured to the wall of the closet adjacent the opening 5. The trackways are braced by means of struts 9 which are also attached to the closet wall above the open-

ing 5. The closure 6 is in the form of a trap door, the door and the closet wall being provided with cooperating means for holding the door in an elevated position when 60 the container for the freezing brine is inserted into the closet.

The receptacle 10 which holds the brine is provided with outturned supporting rim elements 11 adapted to slide on the trackways 65 7. Secured to the outer ends of the rim elements 11 is a face board 12 of such size as to form a closure for the opening 5 in the wall of the closet when the receptacle is in position in the closet.

A chute 13 extends through the face board 12 and leads into the receptacle so that it may be filled after it has been positioned within the closet. A closure 14 for the chute is also provided.

70 Paddles 15 are mounted on a rod 16 to which is connected a lever arm 17 for agitating the contents of the brine containing receptacle. In order that the paddles may be conveniently operated from the exterior 80 of the closet, the lever is extended outwardly into the chute and pivoted to one wall thereof. It is obvious, however, that the lever might be extended through the face board or through a wall of the closet if 85 desired.

A glass window 18 is provided in the face board for inspecting the condition of the outside of the receptacle and handles on the face board are provided for its easy removal.

The function and operation of my improved apparatus for reducing the humidity in a dry storage closet is extremely simple and efficient. The receptacle is inserted into the closet by sliding the rim on the trackways, after which the freezing brine is poured into the chute. As will be apparent, it is desirable that the receptacle be empty when inserted into the closet so that its outer surface will be perfectly dry and thereby in condition to condense the maximum amount of moisture from the air in the closet. When an inspection through the window indicates that the receptacle is covered with moisture or frost it is removed the door 6 dropping down to close the opening.

Having thus described my invention, what I claim as new and desire to secure by Letters Patent is:—

1. In a closet for dry storage, a partition

in said closet spaced from the walls thereof, said closet being provided with an opening in one wall thereof, a refrigerant container adapted to be inserted in said closet through said opening, a support in said closet for said container, a chute connected with said container and means carried by said container for closing the opening in said wall.

5. 2. In a closet for dry storage, said closet

being provided with an opening in one wall thereof, a refrigerant container adapted to be inserted in said closet through said opening, a support for said container secured to said closet wall, a partition secured to said support, and means carried by said container for closing the opening in the wall.

In testimony whereof I affix my signature.

SAMUEL L. RICHMOND.
